UNITED STATES PATENT OFFICE.

JAMES E. TYLER, OF ORANGE COURT-HOUSE, VIRGINIA.

MACHINE FOR EDGING SHEET METAL.

SPECIFICATION forming part of Letters Patent No. 235,817, dated December 7, 1880.

Application filed October 4, 1880. (No model.)

To all whom it may concern:

Be it known that I, JAMES E. TYLER, of Orange Court-House, in the county of Orange and State of Virginia, have invented a new and Improved Machine for Edging Sheet Metal; and I do hereby declare that the following is a full, clear, and exact description of the same.

My invention relates to an improved machine for forming either a single or a double lock upon the edges of sheet-metal plates that may be hooked and pressed together to form a secure joint, either for the manufacture of articles made of sheet metal or for metal roofing and similar purposes; and the improvement consists, essentially, in a pair of reciprocating gripping-jaws, one of which is provided with a lip turned up over the end of the other jaw to hold the edge of the metal sheet between them and pull it beneath a presser-bar, which operation will suffice to form a single fold or lock, and with which device is combined a pivoted bending-jaw that may be forced around the gripping-jaws above referred to, to bend another fold upon the edge of the metal sheet to form a double fold.

My improvement further consists in hinging the gripping-jaws together and providing them with a spring which clamps the edges of the jaws tightly together.

The improvement consists, also, in providing a cam actuated by a lever to overcome the springs and release the work, as hereinafter fully described.

In the accompanying drawings, Figure 1 is a plan view of the machine with the jaws extended ready to receive and gripe the edge of the plate; Fig. 2, a reverse plan view of the same; Fig. 3, a longitudinal section in the line x x of Fig. 1 with the jaws extended; Fig. 4, a similar view of the same with the jaws retracted to make the first fold, and also showing the bending-jaw, in dotted lines, thrown down to make the second fold; Fig. 5, a longitudinal section in the line x x of Fig. 1, showing the jaws extended and the cam forced down upon them to open the gripping-jaws and release the metal from between them.

The machine may be attached to a block of wood, A, secured to a table either in a vertical or a horizontal position, preferably the latter. Guide-plates B are secured to the sides of the

block and underlap its lower edges to form grooves b b , between and into which may rest and freely slide a rectangular gripping-plate, C, to which is secured a link, c, held between guides c' on the bottom of the block A, and connected by a pin, c^2 , with a lever, D, pivoted to the bottom of the block, and formed with a slot, d, in it, by which means the gripping-plate C may be reciprocated between its guides from the position shown in Fig. 1 to that shown in Fig. 4.

The gripping-plate C is formed with a hook-shaped lip, c^3 , turned up to overlap the edge of another gripping-plate, E, hinged to the plate C at F.

G G are spring-plates riveted at one end between the gripping-plates and to one of them, so that the edges or jaws c^3 c^4 of the gripping-plates will be pressed closely together to hold the edge of the plate to be folded.

A presser-bar, H, is secured across the top of the upper gripping-plate, and is secured to ears on the ends of the guide-plates B, so that its face will be parallel to and within the range of contact of a sheet of metal, M, projecting from the jaws of the gripping-plates.

When it is desired to form an open fold or single lap the edge of the sheet metal M is gripped between the jaws by the springs G, as in Fig. 3, and said jaws are then drawn back beneath the presser-bar by the lever, to bend the metal M, as shown in Fig. 4. The plate of metal may then be withdrawn from between the jaws, and is ready to be interlocked with a corresponding plate and hammered or pressed down to form the joint.

In order that the upper gripping-plate, E, may be readily forced down against the springs to release their gripe upon the jaws of the gripping-plates, the presser-bar H may be hinged or pivoted at its ends and provided with a cam-plate, I, and lever K, by which the cam-plate may be partially rotated backward, as in Fig. 5, and forced against the upper gripping-plate, to overcome the pressure of the springs and open the jaws c^3 c^4 .

The cam-plate may extend the entire length of the gripping-jaws, and is curved around the bar H in such manner that it will fold closely around and beneath the jaws of the gripping-plates when rotated forward, as indicated by

the curved arrow in Fig. 4, thus bending the plate M with another fold at its edge so shaped that when united with a plate folded in a similar way the edges will form a double-folded 5 lap-joint.

When the double fold has been made upon the edge of the plate, as above described, the lever K may be reversed, so that the back of the cam-plate will press upon the upper gripping-plate to release its hold upon the plate of sheet metal, and the gripping-plates may be pushed forward so that their jaws will be removed from beneath the presser-bar, in which position, while still pressing upon lever K, the 15 sheet-metal plate may be slid to one side along the length of the jaws until it has been disconnected from them.

When the sheet-metal plate is to be interlocked with a corresponding plate to form a 20 joint their folded edges must be interlocked in the manner just described by placing the edges together at their ends and sliding the plates one across the other.

Various changes may be made in the above- 25 described machine without departing from the spirit of my invention.

What I claim as new is—

1. In a metal-edging machine, the combination of the spring gripping-plates arranged to 30 slide in guides with suitable means for recip-

rocating them, the edge of one gripping-plate being bent to overlap the edge of the other plate, and a presser-bar arranged relatively to the jaws of the presser-plates to bend the plate over as it is drawn beneath it, substantially 35 as described.

2. In a machine for bending the edges of sheet metal to form a double fold, the combination of the spring reciprocating gripping-plates, a presser-bar arranged above the same, and a 40 rotary cam or bending-plate arranged relatively to each other, so that the bending-plate will encircle and pass beneath the edges of the gripping-jaws to turn the second fold in the metal plate, substantially as described. 45

3. In a machine for edging sheet metal, the combination of the gripping-plates C E, hinged together and provided with suitable means for reciprocating them, the presser-springs G, the presser-bar H, and the cam-plate I, and lever 50 K, for operating it to compress the spring-plates and release the work, substantially as described.

The above specification of my invention signed by me this 2d day of October, 1880.

JAS. E. TYLER.
